UNITED STATES PATENT OFFICE.

ERVIN E. STRAWN, OF DES MOINES, IOWA.

LOOSE-LEAF BINDER.

1,292,915.

Specification of Letters Patent. Patented Jan. 28, 1919.

Application filed December 14, 1917. Serial No. 207,165.

To all whom it may concern:

Be it known that I, ERVIN E. STRAWN, a citizen of the United States, residing at Des Moines, in the county of Polk and State 5 of Iowa, have invented new and useful Improvements in Loose-Leaf Binders, of which the following is a specification.

This invention relates to loose leaf binders and the object is to provide improved means 10 for securing the sheets to the cover, said means comprising a plurality of flexible devices so positioned that they register with slots or apertures formed in the sheets, the flexible devices being engaged by detachable 15 staples or the like formed of resilient material.

With the foregoing and other objects in view, the invention consists in the novel construction, combination and arrangement 20 of elements hereinafter described and claimed:

In the drawings:

Figure 1 is a plan view showing the binder open with leaves secured therein by my im- 25 proved fastening device.

Fig. 2 is a section on the line 2—2 of Fig. 1.

Fig. 3 is a detail view of the fastening device of Fig. 1.

Fig. 4 is a fragmentary view showing another form of fastening device.

Fig. 5 shows the fastener of Fig. 4 detached.

Fig. 6 is a detail of a further modifica- 35 tion.

In carrying out my invention I employ a binder comprising outer cover members 10 and 12 connected by means of a flexible strip 13 in any suitable manner, a plurality of 40 flexible devices 14 and 15 extending transversely of the cover members and across their line of connection being secured beneath the strip above mentioned. In the drawings I have shown two of these flexible 45 devices 14 and 15, and it is obvious that the number may be varied as desired.

One of the sheets to be secured to the binder is designated 18, this sheet being folded along a line 19 and being provided 50 with apertures or slots 20 extending transversely of the fold 19. The flexible devices or tapes 14 and 15 extend through these slots to a slight degree and are engaged by a plurality of spring members or staples design- 55 ated 22 for taking up slack in the tapes and each comprising a substantially straight

portion 23, a deflected end portion 24 and an oppositely located member including portion 25 and deflected portion 26 of the form shown, for engaging members 14 and 15. 60 These members 22 are formed of resilient material and are designed to engage the flexible devices in the manner shown in the drawing, whereby the loose sheets will be properly held in position and may readily 65 be removed if desired. Additional sheets may be inserted from time to time as required by removing the staples and reinserting them after the sheets are in position.

In Figs. 4 and 5 I have shown another 70 form of spring including a loop 28 and a plurality of members adapted to extend in approximately parallel relation, one of these members being longer than the other and designated 29, said member having a hook 75 30 formed at the end, and the opposite member 31 having a small hook 32 formed at the end. Each of these members is provided with deflected portions forming small loops and corresponding projecting members, positioned opposite each other, the projecting members of one branch of the staple being designated 33 and the other branch thereof 34. These members 33 and 34 are 80 designed to pass through the flexible devices 85 14 and 15 when the staples are in securing position.

A device constructed as illustrated is inexpensive and unusually efficient, the spring members providing for an increase or decrease in the number of sheets, and providing for taking up slack when the binder is closed, and said spring members when in position securely retaining the sheets and at the same time permitting of their prompt 95 removal when desired.

A student employing the device for making notes in different classes may use a number of these sheets in a single binder, one or more sheets being devoted to a single subject, and may then transfer the proper sheets to separate permanent binders for keeping a permanent record of his notes relating to each subject. A unit of about 24 sheets may be used and transferred in the manner indicated.

In Fig. 6, I have shown another form of the spring fastening device, including a straight portion 37, and an oppositely located portion in the form of a compound curve 110 38, and 40. The element 37 is deflected at 39 as shown.

I claim:—

1. In a device of the class described, a cover, a plurality of flexible devices extending transversely of the hinged portion of the cover, said devices forming loops, a plurality of sheets provided with apertures at the line of the fold thereof and positioned to register with the flexible devices when the sheets are in position in the cover, and a plurality of devices for engaging the flexible devices and adapted to be passed between the latter and the inner surface of the sheets to be secured, said devices comprising bifurcated members, the arms of which are

provided with engaging devices adapted to 15 hold the staple members in position within the flexible devices.

2. In a device of the class described, a cover, a plurality of flexible devices mounted therein, a plurality of folded sheets having 20 apertures formed therein at the line of the fold the apertures registering with the flexible devices, and resilient devices each including a plurality of longitudinally extending leg members, said resilient devices 25 taking up the slack in the flexible devices.

In testimony whereof I affix my signature.

ERVIN E. STRAWN.
